CLAIM

The ornamental design for a hydraulic power unit having fill port, as shown and described.

DESCRIPTION

FIG. 1 is a front perspective view of the hydraulic power unit having fill port showing the new design.

FIG. 2 is a top plan view of the hydraulic power unit having fill port.

FIG. 3 is a bottom plan view of the hydraulic power unit having fill port.

FIG. 4 is a first side view of the hydraulic power unit having fill port.

FIG. 5 is a second side view of the hydraulic power unit having fill port.

FIG. 6 is a third side view of the hydraulic power unit having fill port; and,

FIG. 7 is a fourth side view of the hydraulic power unit having fill port.

(Continued)

The broken line showing portions of the hydraulic power unit having fill port form no part of the claimed design.
